US0D1056469S

(12) **United States Design Patent** (10) **Patent No.:** **US D1,056,469 S**
(45) **Date of Patent:** **** Jan. 7, 2025**

(54) **BAG**

(71) Applicant: **FURLA S.p.A.**, San Lazzaro di Savena (IT)

(72) Inventor: **Fabio Fusi**, Bo (IT)

(**) Term: **15 Years**

(21) Appl. No.: **35/514,311**

(22) Filed: **May 6, 2022**

(80) **Hague Agreement Data**

Int. Filing Date: **May 6, 2022**

Int. Reg. No.: **DM/220643**

Int. Reg. Date: **May 6, 2022**

Int. Reg. Pub. Date: **May 20, 2022**

(51) **LOC (15) Cl.** **03-01**

(52) **U.S. Cl.**

USPC **D3/243**
